UNITED STATES PATENT OFFICE.

EDWARD D. HARSEN, OF BROOKLYN, ASSIGNOR TO THE MINING AND DREDGING POWER COMPANY, OF NEW YORK, N. Y.

STEAM-VACUUM DREDGER.

SPECIFICATION forming part of Letters Patent No. 514,598, dated February 13, 1894.

Application filed May 4, 1891. Renewed May 11, 1892. Again renewed July 15, 1893. Serial No. 480,664. (No model.)

To all whom it may concern:

Be it known that I, EDWARD D. HARSEN, a citizen of the United States, residing in Brooklyn, in the county of Kings and State of New York, have invented certain new and useful Improvements in Steam-Vacuum Dredgers, of which the following is a specification.

This invention relates to that class of dredging apparatus or pumps which are primarily used for dredging and mining, and in which the pressure of the atmosphere is utilized to elevate débris or any other semi-liquid material into a vacuum chamber, the vacuum being formed in the pump by the condensation of steam, and in which steam pressure is then used to force the material out of the pump and lift it to the required height; and the invention consists of a steam vacuum dredging apparatus, which comprises a pump-chamber supported on a base which is connected at one end with a suction pipe and at the other end with a discharge pipe, said suction and discharge pipes being provided with gate-valves that are guided in valve-chambers and operated by means of pistons arranged in cylinders supported on laterally extending brackets of the pump-chamber.

The invention consists further, in the construction and arrangement of parts, hereinafter fully set forth and finally pointed out in the claims.

In the accompanying drawings, Figure 1 represents a side elevation of my improved steam vacuum dredger, shown with a portion 35 of the suction-pipe valve-chamber broken away; and Fig. 2 is a vertical transverse section of the cylinder and piston for operating one of the gate-valves.

Similar letters of reference indicate corresponding parts.

In the drawings, A A represent steam-cylinders provided with cylinder-heads A' A² and steam-chests a⁷, as shown; and with the steam-ports a² and a³, and exhaust-ports a⁴ 45 a⁴, whereby the up or down movement of the pistons p is regulated by the manipulation of the valves h h of the steam-pipe H. Each valve h is constructed so as to freely admit the steam through the pipe H into the chest a⁷ at all times; but, by the manipulation 50 thereof, as by means of the lever h⁸ and link

h⁴, connected with the valve-stem h', the bar h² (one end of which is rigidly attached to the valve-stem h' and the outer extremity of which is pivoted at a⁶ to the slide-valve a⁵ 55 within the chest a⁷) is moved so as to admit the steam, passing from the pipe H into the chest a⁷, either into the port a³ or the port a², according to the position of the slide-valve a⁵; the steam being allowed, after performing 60 its work in moving the piston within the cylinder A, to escape through the exhaust a⁴, in the manner well known in the art.

At the lower extremities of the piston-rods B B, are gate-valves C C. These vertical 65 gate-valves are constructed with parallel sides, and work in grooves e e, and are planed or trued so as to slide smoothly through the stuffing-boxes E E; the tops of which latter are provided with glands F F, the upper 70 parts F² of the same being formed in funnel shape in order to contain water. The object of allowing water to remain in the funnel-shaped boxes is to make the valves tight, as water will then be drawn in instead of air; 75 and the frequent renewal of packing will be avoided and the apparatus enabled better to pump with the water sand and stones and grit of all kinds held in suspension therein.

The grooves e e are preferably formed by 80 ways e', which may be bolted to the sides of the channel-way of the valve-chambers D' D', and which serve to guide the gate-valves C C in their stroke up and down. The gate-valves C C also conform in size to the general shape 85 of the channel-way of the valve-chambers D' D', and move freely in the ways e'.

The upper end of each piston rod B passes 90 upwardly from the piston p, through a stuffing-box A⁴ in the top head A' of the cylinder A; and is provided with a head p' which works in a cylindrical dash-pot J; the two extremities of each dash-pot being connected by a pipe j, in which is a valve j'. The dash-pots J contain water; and the violent concus- 95 sion in opening either of the gate-valves C C is prevented by means of the pressure upon the water in forcing the same from one end of the cylinder to the other through the pipe j, a water-cushion being thus formed. The 100 flow of the water may be regulated by means of the valves j'.

- The valve-chambers D' D' are made integral with or attached by rivets to each end of a base D, which is also provided with an interior channel-way conforming to those of the 5 valve-chambers D' D', and which is surmounted by a vacuum-cylinder G, that is cast with or bolted on the same. The base D is arranged in line with the valve-chambers D' D' and with the suction and discharge-pipes D² and 10 D³ so that they form a continuous channel-way from the suction-pipe through one valve chamber D' to the base of the pump-chamber when the suction gate-valve C is opened and the discharge-valve closed, and another continuous channel-way from the base D through 15 the discharge valve-chamber D' to the discharge-pipe D³, when the discharge gate-valve is opened and the suction gate-valve closed. This arrangement facilitates the free and unobstructed movement of the material when 20 it is sucked into the pump chamber by the vacuum and when it is expelled by the action of the steam admitted into the pump-chamber. The absence of corners and angles permits 25 the easy movement of the material without any unnecessary obstructions being placed in its path, so that the pulsating action of the pump is facilitated and its effectiveness increased.
- 30 The steam-cylinders A A are attached to the sides of the pump-chamber G by means of the brackets g³ a. The pump-chamber G is also provided with a valved water-pipe g, valved steam-pipe g', and valved exhaust pipe g². The steam pipe H serves to supply steam to the pump-chamber G and to the steam-cylinders A A.
- The operation of the parts is as follows: 35 The left-hand suction gate-valve C being opened and the entrance of the suction-pipe D² leading thereto, being submerged; and the right-hand discharge gate-valve C being closed, or in positions the reverse to that shown in the drawings; a vacuum is formed in the pump-chamber G by first filling it with steam and then condensing the steam by the admission of cold water. The submerged end being placed below the level of the ground, or in a pit filled with mixture of water 40 and gravel or other solid material, the pressure of the atmosphere will force the semi-liquid material through the suction-pipe and valve-chamber D' into the pump-chamber G. When the vacuum chamber G is filled, steam is again let into it through the valve g'; and, simultaneously, the left-hand suction gate-valve C is closed and the right-hand discharge gate-valve C is opened, the parts now being in the positions represented in the drawings; and the material is thereby discharged 45 through the valve-chamber D', and may be

forced to an elevation of fifty to one hundred feet above the level of the ground thus making an artificial grade or dump for the débris. After this discharge, the parts are reversed, 65 and the operation is again gone through.

My invention may be utilized for other purposes than those mentioned, being applicable wherever atmospheric pressure is used for moving or elevating any semi-liquid material. 70

The controlling-valves h h g' g² may be operated manually independently or in pairs; or they may be operated automatically, by the use of a ball or float placed within the pump-chamber G in the manner well known 75 in the art and adapted to properly operate the valves when the pump-chamber is emptied and when it becomes partially filled with water.

As it is evident that many slight changes in the construction and relative arrangement of parts might be resorted to without departing from the spirit and scope of my invention, I would have it understood that I do not restrict myself to the particular construction and arrangement of parts shown 80 and described; but

What I claim as new, and desire to secure by Letters Patent, is—

1. The combination, of a pump-chamber having a suction-pipe and a discharge-pipe, 90 gate-valves in said suction and discharge-pipes, cylinders for operating said gate-valves, mechanism for controlling the slide-valves of the cylinders, and valved pipes for admitting steam and water to the pump-chamber, substantially as set forth.

2. The combination, of a pump chamber, a base for the same, a suction-pipe at one end and a discharge-pipe at the other end of the base, valve-chambers in said pipes, gate-valves guided in said valve-chambers, and steam-cylinders the piston-rods of which are connected with said gate-valves for operating the same, said base and valve-chambers forming a continuous and uninterrupted channel 105 way with the suction and discharge-pipes, substantially as set forth.

3. The combination, with the pump-chamber having a suction-pipe and a discharge-pipe, of valve-chambers in said pipes, gate-valves in said valve-chambers, cylinders for operating said gate valves, and dash-pots above the cylinders having pipes connecting the ends of the dash-pots for cushioning the gate-valves, substantially as set forth. 110

In testimony that I claim the foregoing as my invention I have signed my name in presence of two subscribing witnesses.

EDWARD D. HARSEN.
